METHOD FOR GRAINING EXPLOSIVE COMPOSITIONS

Willard de C. Crater, Succasunna, N. J., assignor to Hercules Powder Company, Wilmington, Del., a corporation of Delaware

No Drawing. Application January 19, 1932,
Serial No. 587,608

8 Claims. (Cl. 52—20)

This invention relates to a method for graining explosive compositions and the product produced thereby.

As is well known, explosive compositions are desirably prepared for use in a free flowing form in order that they may be easily loaded. The capacity to flow freely is of the greatest assistance in connection with explosive compositions adapted, for example, for the loading of blasting caps. 10 Heretofore certain explosive compositions have been provided in a free flowing form by crystallization from a solution, but, as is well known, many explosive compositions and especially organic explosive compositions, have not heretofore 15 been susceptible of easy preparation in a free flowing form due to the fact that they cannot be made free-flowing by crystallization, but can only be produced in this form by costly or dangerous operations, as, for example, by tumbling 20 in a mixer, or, for example, spraying with a gum solution followed by drying.

Now, it is the object of this invention to provide a method whereby explosive compositions may be readily prepared in a free-flowing form 25 without danger and with economy. This invention also contemplates the product of the method, which is distinguished by its granular form, which renders it free-flowing and hence capable of ready and efficient loading and by the fact 30 that it is dustless.

The method in accordance with this invention will be found to be more especially adaptable to organic explosive compositions, which as a class are more generally not susceptible to crystallization in a free-flowing form.

The method in accordance with this invention involves broadly the addition to water maintained at an elevated temperature of a solution of an explosive composition to be prepared in a free flowing form in a solvent or mixture of solvents 40 which is immiscible with water.

In accordance with this invention various explosives may be produced in a free flowing form, though, as has been indicated, the invention will 45 be found to be most advantageous in the case of those explosive compositions, more especially organic explosive compositions, which resist crystallization in a free-flowing form.

Thus, by way of illustration, the method in accordance with this invention, will be found to be applicable to, for example, nitrolactose, as lactose octanitrate, pentaerythrite nitrate, as pentaerythrite tetranitrate, tetranitromethylamine or tetryl nitrotoluene as trinitrotoluene.

55 The method in accordance with this invention

will also be found to be applicable to the production of mixtures of explosive or to an explosive with stabilizers and other solids in uniform, homogeneous, free-flowing form. Thus, by way of illustration, the invention will be found applicable to, for example, mixtures of nitrolactose, trinitrotoluene and diphenylamine. As will be understood, this invention will be found applicable to various mixtures of explosive compositions or to an explosive with another solid or solids. Thus, 10 for example, in the above illustration the diphenylamine may be replaced with, for example, diethyl diphenylurea, dimethyl diphenylurea, etc., etc. and the trinitrotoluene may be replaced with, for example, dinitrotoluene, tetryl, dinitrobenzene, etc., etc. In the treatment of explosive compositions in accordance with this invention various other solids may be combined with an explosive composition or mixture of explosive compositions, as, for example, graphite, antimony sulfide, copper sulfide, etc.

In carrying out the method in accordance with this invention, the explosive composition or mixture of explosive compositions or mixture of explosive composition and stabilizer or other solid 25 to be produced in free-flowing form will be dissolved in a solvent or solvent mixture. Any suitable solvent or solvent mixture for the explosive composition or mixture to be treated and which is immiscible with water, may be used. 30

Thus, by way of illustration, a mixture of ether and acetone, the ether being in quantity such that the mixture will be substantially immiscible with water may be used as a solvent for lactose octanitrate, tetryl, a mixture of nitrolactose, 35 trinitrotoluene and diphenylamine. Ethyl acetate may be used as a solvent in connection with the treatment of pentaerythrite tetranitrate and also of tetryl. Thus, it will be understood that any solvent or solvent mixture suitable for dissolving the explosive composition, or mixture of explosive compositions, or of explosive compositions and other solids to be incorporated therewith, as, for example, stabilizers and which is substantially immiscible with water may be used. 40

As has been indicated, a solution of the explosive composition or mixture, etc. to be produced in a free-flowing form will be added to water maintained at an elevated temperature. The temperature of the water may vary widely, 50 depending upon the particular solvent or solvent mixture used, the purpose of an elevated temperature being to eliminate the solvent upon the addition of the solution to the water. Thus, by way of illustration, the temperature of the water 55

may be within say, for example, the range 50-85° C., it being understood, of course, that temperatures outside of such range may be used where the character of the solvent or solvent mixture used is such that it will be eliminated at a temperature outside of such range.

The method in accordance with this invention may be carried out without the use of any special form of apparatus. However, by way of example, the invention may be desirably carried out in a closed kettle jacketed for a heating medium and equipped with a bottom outlet and a stirrer or agitating device the speed of which may be controlled. The kettle will desirably be provided with a condenser for recovery of solvent or solvent mixture and with an inlet for addition of the solution, the inlet being desirably provided with a valve enabling regulation of the admission of the solution.

As illustrative of the practical adaptation of the method embodying this invention, for example, 1000 grams of lactose octanitrate are completely dissolved in a mixture of 2500 cc. of ether and 200 cc. of acetone. The solution will desirably be filtered to remove any foreign substances and then will be added slowly to 3 liters of water heated to a temperature of say about 55° C. with rapid stirring. The temperature is maintained and the stirring is continued until the solvent mixture ceases to come off. As the solvent goes off the nitrolactose will be precipitated in the form of grains and when the solvent ceases to come off the water may be cooled to harden the grains of nitrolactose. The nitrolactose is then separated from the water and dried in any suitable manner. The dried material will be in the form of grains of substantially uniform size and will be free flowing and dust free.

As illustrative of the granular form of the nitrolactose treated in accordance with the above illustration and as indicative of its free flowing condition reference is made to the following screen test of the product:

	Percent
Held on 20 mesh	5.28
Held on 30 mesh	29.25
Held on 40 mesh	35.50
Held on 50 mesh	10.90
Held on 60 mesh	7.75
Passing 60 mesh	11.32

As a further illustration, for example, 25 grams of tetryl are dissolved in 300 cc. of ether and 75 cc. of acetone. The solution is filtered to remove foreign substances if necessary and then added slowly with agitation to a body of water maintained at a temperature of say about 60° C. The temperature is maintained and the stirring continued until the solvent mixture is evaporated off and the water is then cooled to harden the grains of tetryl. The grains are separated from the water and after suitable drying will be found free-flowing and dust proof. Alternatively, 25 grams of tetryl may be dissolved in 200 cc. of ethyl acetate and run into water maintained at a temperature of 80-85° C. with agitation, the granular tetryl being separated from the water, cooled and then dried in any suitable manner. As a further illustration, for example, 25 grams of pentaerythrite tetranitrate are dissolved in 250 cc. of ethyl acetate and the solution run into water maintained at a temperature of say 80-82° C., the water being cooled after the solvent is evaporated off to harden the grains

and the granular material being separated from the water and treated as above described.

As a further illustration, 50 grams of trinitrotoluene dissolved in a mixture of 300 cc. of ether and 100 cc. of acetone may be given a granular, free-flowing form by running into water maintained at a temperature of about 60° C., the water being cooled after the solvent is evaporated off and the granular material is separated and dried as described.

As illustrative of the application of this invention to mixtures, for example, 950 grams of nitrolactose, 50 grams of trinitrotoluene, 7.5 grams of diphenylamine and 10 grams of graphite are added to a mixture of 2500 cc. of ether and 200 cc. of acetone. All but the graphite will be dissolved in the solvent mixture, the graphite remaining in suspension. The solution formed containing the graphite in suspension is added to 3 liters of water at about 55° C. The mixture of explosive compositions (nitrolactose and trinitrotoluene) and the stabilizer (diphenylamine) will, on evaporation of the solvent, be precipitated in homogeneous admixture in the form of grains, with the graphite incorporated throughout the grain. After the solvent is evaporated, the water is cooled, the grained product separated from the water and dried in any desired manner.

As has been indicated, various mixtures of explosive compositions and of explosive compositions and other substances desired to be included therewith, as, for example, stabilizers or other solids, may be produced in free flowing form by the method embodying this invention.

It is understood that the method in accordance with this invention will have general application to explosive compositions, mixtures thereof and mixtures thereof with other substances being especially adaptable to the treatment of explosive compositions which resist crystallization in a free-flowing form or the crystallization of which involves danger and expense and will be found more especially adaptable to the treatment of organic explosive compositions.

It will be understood that the product of the method embodying this invention is contemplated as embodying the invention, the product as indicated being recognized by its granular form resultant from the treatment, whether the product include only a single explosive composition or a plurality of explosive compositions and an explosive composition or compositions with another substance, as, for example, a stabilizer, homogeneously combined.

It will be understood that in carrying out the method in accordance with this invention various solvents and temperatures, depending upon the solvent, may be used for the treatment of various explosive compositions, the solvents, temperatures, etc., etc. given in connection with the above description and illustrations of the practice of the method being merely for purposes of illustration.

It will be understood that where in the claims appended hereto the term "solvent" is used, it is intended to include solvent mixtures as equivalents.

What I claim and desire to protect by Letters Patent is:

1. The method of graining a crystalline organic explosive compound which includes dissolving the explosive compound in a solvent which is substantially immiscible with water and evaporating the solvent in the presence of water

heated to a temperature at which the solvent will be evaporated.

2. The method of graining a crystalline organic explosive compound which includes dissolving the explosive compound in a solvent which is substantially immiscible with water and introducing the solution into a body of water heated to a temperature at which the solvent will be evaporated while agitating the body of water.

10 3. The method of graining a crystalline organic explosive compound which includes dissolving the explosive compound in a solvent which is substantially immiscible with water and which will boil at a temperature within the 15 range 50-85° C. and introducing the solution into a body of water heated to a temperature within the range 50-85° C.

4. The method of graining a crystalline organic explosive compound which includes dissolving the explosive compound in a solvent which is substantially immiscible with water, introducing the solution into a body of water heated to a temperature at which the solvent will be evaporated, separating the precipitated 25 explosive compound from the water and drying the explosive compound.

5. The method of graining an explosive mixture containing a crystalline organic explosive compound which includes dissolving the explo-

sive mixture in a solvent which is substantially immiscible with water and introducing the solution into a body of water heated to a temperature at which the solvent will be evaporated.

6. The method of graining nitrolactose which includes dissolving nitrolactose in a solvent which is substantially immiscible with water, introducing the solution into water heated to a temperature at which the solvent will be evaporated, separating the precipitated 10 nitrolactose from the water and drying the nitrolactose.

7. The method of graining a crystalline organic explosive compound and a substance to be incorporated therewith which includes dissolving the explosive compound and the substance 15 to be incorporated therewith in a solvent therefor which is substantially immiscible with water and introducing the solution into a body of water heated to a temperature at which the solvent will be evaporated.

8. The method of graining a crystalline organic explosive compound and a stabilizer which includes dissolving the explosive compound and the stabilizer in a solvent therefor which is substantially immiscible with water and introducing the solution into a body of water heated to a temperature at which the solvent will be evaporated.

WILLARD DE C. CRATER.
